DESIGN FOR A COLLAR HOLDER

Irving J. Hopfenberg, Providence, R. I.

Application April 9, 1945, Serial No. 118,915

Term of patent 14 years

(Cl. D17—10)

To all whom it may concern:

Be it known that I, Irving J. Hopfenberg, a citizen of the United States, residing at Providence, in the county of Providence and State of Rhode Island, have invented a new, original, and ornamental Design for a Collar Holder, of which the following is a specification, reference being had to the accompanying drawing, forming part thereof.

Fig. 1 is a plan view of a collar holder, showing my new design;

Fig. 2 is a side view of the same;
Fig. 3 is a bottom view of the same; and
Fig. 4 is an end view of the same.
I claim:
The ornamental design for a collar holder, as shown.

IRVING J. HOPFENBERG.
